(57) **CLAIM**

The ornamental design for a pressure activation device, as shown and described.

DESCRIPTION

FIG. 1 is a perspective top view of the “pressure application device” with a rounded contact point at the top vertex of the device;

FIG. 2 is a front side view of the “pressure application device”, the front side view is a mirror image of the rear side view, the right side view and the left side view;

FIG. 3 is a top view of the “pressure application device”; FIG. 4 is a bottom view of the “pressure application device”; FIG. 5 is a perspective bottom view of the “pressure application device” with rounded corners along the base of the device;

FIG. 6 is a perspective bottom view of the “pressure application device” with a flat bottom trim transitioning each side of the device to the base of the device;

FIG. 7 is a perspective bottom view of the “pressure application device” with pointed corners along the base of the device; and,

FIG. 8 is a perspective top view of the “pressure application device” with a rounded contact point at the top vertex of the device and a pointed tip and a flat bottom trim transitioning each side of the device to the base of the device.
